UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,233,147.

Specification of Letters Patent. Patented July 10, 1917.

Application filed April 14, 1917. Serial No. 161,999.

To all whom it may concern:

Be it known that I, HENRY G. VOIGHT, of New Britain, county of Hartford, and State of Connecticut, have invented certain new and useful Improvements in Locks, of which the following is a full, clear, and exact description.

This invention has reference to door locks and it pertains more especially to locks of the type in which a latchbolt is retractable from opposite sides of the door by separate knobs or other manually operable devices, there being suitable stopwork associated with the hub of the outer knob so that the latter may be dogged to prevent opening of the door from the outside through the retraction of the latch.

In some instances locks of this character have been attacked by throwing off the stopwork or night-latch mechanism by a wire or like instrument inserted between the jamb and the face plate, and it has been proposed to remedy this objection by providing an auxiliary dogging means for the outer hub which is operated automatically on the closing of the door, when the ordinary stopwork is in the operative position, to dog the outer hub independently of said stopwork so that the door cannot be opened by a burglar even if the regular stopwork is attacked and operated in the manner above mentioned.

One of the primary objects of the present invention is to furnish a lock, of the general character last stated, in which the automatic dogging mechanism for the outer hub or its equivalent is especially simple, reliable and easy to manufacture and assemble.

A still further object of the invention is to provide a lock, of the character stated, in which the stopwork is provided with means for positively and automatically locking the automatic hub dogging device in its inoperative position when the stopwork is thrown off during the time that the door is open.

To these and other ends the invention consists in the novel features and combinations of parts to be hereinafter described and claimed.

In the accompanying drawing,

Figure 1 is an elevation of a mortise lock embodying the invention, with the cap plate removed, showing the stopwork dogging the outer hub, the door being open. 55

Fig. 2 is a view similar to Fig. 1 but showing the door closed and the outer hub dogged by the automatic dogging device.

Fig. 3 is a view showing the ordinary stopwork released, with the door closed, the 60 automatic dogging device for the outer hub remaining, however, in the operative position.

Fig. 4 is a view showing the automatic dogging lever for the outer hub, locked in 65 the inoperative position by the stopwork.

Fig. 5 is a detail reverse view of the lower part of the lock, showing the dogging slide, hubs, etc., and

Fig. 6 is a detail section on line 6—6 of 70 Fig. 1.

Referring to the drawings, 20 is a mortise lock case having the customary latchbolt 21, the shank or stem 22 of which is provided at the rear end with a cross head 75

23 engaged, in the ordinary manner, with the usual knob-actuated retracting yoke 24. The yoke 24 may be actuated by means of an outer hub 25 and an inner hub 26 connected with the usual knob spindles (not 80 shown). In the form shown, the latchbolt 21 may be actuated by means of a lever 27 engaged with a crosshead 23, and adapted to be operated by suitable key mechanism which it is not necessary to illustrate. The 85

outer knob may be dogged by night-latch mechanism or stopwork of the usual type coöperating with the outer hub 25 and comprising the customary dogging slide 28, walking beam 29, and releasing slide 30, 90 the slides 28 and 30 being provided with the usual heads or buttons projecting through openings in the face plate so that the stopwork can be actuated from the lock front in the ordinary way. When the door 95 is closed, the latchbolt 21 is automatically dogged in the customary manner by means of a dogging or guarding lever 31 controlled by a guard bolt or controller bolt 32 projecting through the face plate and 100

adapted to be pressed inward by contact with the strike 33, as shown in Fig. 2. As the controller bolt is forced inward by contact with the strike, a lug 34, carried at the lower end of a depending plate 35 on the shank of the spring-pressed controller bolt, is moved rearwardly to permit the dogging lever 31 to be swung into dogging position, relatively to the latchbolt, by means of its spring 36. When the door is open, the lug 34, on the controller bolt, engages the dogging lever at such a point as to hold it up out of the path of the latchbolt head.

All of the parts so far described are old and wellknown, and form in themselves no part of the present invention.

The automatic dogging means for the outer hub 25 comprises, preferably, an elbow lever 37 pivoted on a post 38 and carrying at its lower end a lug or extension 39 adapted to engage the notch 40 which is engaged by the dogging slide 28. The lever 37 overlies the slide 28, the yoke, the latchbolt, and the dogging lever 31, and the lug 39 lies close to the inner end of the dogging slide 28 in such relation to the outer hub that the latter can be dogged simultaneously by the slide and by the lever, both of which may extend into the notch 40. A spring 41 carried by the lever reacts against the post 42 (which, incidentally, is the pivot post for the dogging lever) and tends to hold the lever 37 in the notch of the outer hub. The lever is held out of the notch, however, when the door is open by the controller bolt 32, the lug 34 of which underlies the upper end portion of the lever 37 and controls it in much the same manner that the bolt dogging lever is controlled. For this purpose the upper end portion of lever 37 is provided with a shoulder 37^a which engages the upper surface of lug 34 when the door is open to hold up the upper end of the lever so that its lower end will be free of the hub 25. When, however, the door is closed, and the controller bolt is thrust inward, the lug 34 moves into a recess 37^b and consequently the spring 41 is permitted to act, thereby forcing the lug 39 into the notch 40 and dogging the outer hub against rotation.

The upper end of lever 37 is provided with a small notch 44, adapted to be engaged by a pin 45 extending laterally from the shank of the releasing slide 30 of the stopwork.

The operation of the lock will be more or less obvious from the foregoing description. When the door is closed, the controller bolt, in being forced inward by the strike, is shifted to such a position as to permit the dogging lever 37 to be moved to its operative position by the spring 41. The guarding mechanism for the latchbolt 65 is actuated in a similar manner. Supposing

the parts to be in the position shown in Fig. 2, if a burglar succeeds in introducing an instrument between the face of the lock and the door jamb and exerting pressure on the head of the releasing slide 30 to reverse the stopwork, this will not release the outer knob owing to the fact that the outer hub continues to be dogged by the lever 37. Therefore the burglar cannot gain access to the room, or house, even if he succeeds in throwing off the stopwork.

When the door is open the dogging lever 37 stands out of the notch in the outer hub, owing to the provision of the controller bolt, regardless of the position of the regular stopwork, but if the stopwork is thrown off at this time by an unauthorized person, the pin 45 on the releasing slide enters the notch 44 of the dogging lever and the latter is thereby firmly held in inoperative position until such time as the ordinary stopwork is thrown off again and the door is closed.

Various changes may be made in the details of the construction without digressing from the invention as set forth in the claims.

What I claim is,

1. In a lock, a case, a latchbolt therein, means within the case and including a hub for retracting said latchbolt, a member within the case to dog said hub directly, a spring acting on said member and normally holding it in dogging relation to said hub, and a spring-pressed controller bolt projecting from the case, normally holding said dogging member out of its operative position in opposition to said spring when the door is open.

2. In a lock, a latchbolt, a retracting device therefor, a spring-pressed member normally dogging said retracting device, a spring-pressed member normally dogging said latchbolt, and a spring-pressed controller bolt projecting out of the case and normally holding both of said members in the inoperative position.

3. In a lock, a latchbolt, a manual retracting device therefor, a spring-pressed lever normally tending to dog said device, a spring-pressed lever normally tending to dog said latchbolt, and a spring-pressed projecting controller bolt having a portion underlying both of said levers when the door is open and holding them both in an inoperative position in opposition to their springs.

4. In a lock, a latchbolt, a hub for retracting the same, stopwork to dog and release said hub, including a dogging slide and a releasing slide, automatic dogging means for said hub operated on the closing of the door, and means on the releasing slide of said stopwork for dogging said automatic means in the inoperative position when the door is open and said stopwork is released.

5. In a lock, a latchbolt, a hub for re-
tracting the same, stopwork to dog and
release said hub, including a dogging slide
and a releasing slide, a spring-pressed dog-
ging lever normally dogging said hub, a
spring-pressed controller holding said lever
in an inoperative position while the door is
open, and a pin on the releasing slide for
holding said lever in the inoperative position
when the stopwork is in the released posi- 10
tion.

In witness whereof, I have hereunto set
my hand on the 12th day of April, 1917.

HENRY G. VOIGHT.
